UNITED STATES PATENT OFFICE.

JAMES A. CAMERON AND GUSTAF BIRGER BIRCH, OF BROOKLYN, NEW YORK, ASSIGNEES TO CAMERON MACHINE COMPANY, OF BROOKLYN, NEW YORK, A CORPORATION OF NEW YORK.

SLITTING AND REWINDING MACHINE.

1,354,463.

Specification of Letters Patent.

Patented Oct. 5, 1920.

Application filed May 7, 1917, Serial No. 166,796. Renewed July 17, 1920. Serial No. 397,149.

To all whom it may concern:

Be it known that we, JAMES A. CAMERON and GUSTAF B. BIRCH, citizens of the United States, and residents of the borough of Brooklyn, in the county of Kings, city and State of New York, have invented certain new and useful Improvements in Slitting and Rewinding Machines, of which the following is a specification.

10 This invention relates to slitting and rewinding machines.

In the art of slitting and rewinding sheet material a successful type of machine embodies the mechanism shown in Patent No.

15 1,076,189, in which a pair of rewinding rolls supports the rewound coils and coöperates with a third roll engaging the upper periphery of the coils to rotate the coils and thereby perform the rewinding operation. In

20 this type of machine one of the rewinding rolls on which the rewound coils are supported is utilized also as a cutter roll and for this purpose is provided with a shell made up of cylindrical sections having a

25 glass-hard surface. Because of the great difficulty of uniformly and properly hardening the surface of a section having a large diameter, it has been found necessary to restrict as far as possible the diameters of the

30 sections. With the development of the art, however, a point has been reached in which a cutter roll having a diameter small enough to comply with the limitations of the hardening process can not be used as a sup-

35 porting roll for the rewound coils because of its tendency to bend under the weight of the coils and thereby interfere with both the slitting and the rewinding operations. In the co-pending application Serial No.

40 146,569 there is shown a construction of slitting and rewinding machine in which a cutter roll of relatively small diameter is provided, which does not engage the rewound coils, but, instead, is mounted in the frame-

45 work of the machine beneath a pair of rewinding rolls of relatively large diameter.

The main object of this invention is to provide means for so mounting the cutter roll in the body of the machine that access can be had thereto to remove or replace the roll in whole or in part without dismantling the machine framework.

With this and other objects in view the invention consists principally in providing one

of the machine frame members with an opening through which the cutter roll can be passed and in making use of a bearing member for supporting one end of the cutter roll shaft in said opening.

Other features of the invention will be referred to as the specification proceeds.

In the accompanying drawing, wherein there is shown one of the many possible embodiments of the invention,

Figure 1 is a vertical section of a portion of a machine, embodying the invention, taken along the line 1—1 of Fig. 2.

Fig. 2 is a vertical section of the machine taken along the line 2—2 of Fig. 1 and showing the driving connection between the cutter roll and the top rewinding roll.

Fig. 3 is a horizontal section of a part of the machine taken along the line 3—3 of Fig. 1.

Fig. 4 is a horizontal section taken through the removable mounting device for the cutter roll at 4—4 of Fig. 1.

In the particular embodiment of the invention disclosed, coil supporting rewinding rolls of relatively large diameter are employed and, in lieu of adapting one of these rolls to serve also as a cutter roll, a special cutter roll is provided, as in application Serial No. 146,569, which serves only as a cutter roll and takes no part in the rewinding operation.

The cutter roll is preferably mounted beneath and intermediate the rewinding rolls with its ends journaled within the boundaries of the heavy framework of the machine and, in order to provide access to the cutter roll for any purpose, such as the replacement of the roll in whole or in part without dismantling the machine framework, one of the frame members in

which the cutter roll is mounted is provided with an opening of such size that the cutter roll can be passed therethrough. To directly support one end of the cutter roll and provide a bearing therefor, a bearing member is provided which is removably attached to the framework in such a way as to extend into the opening. Provision is also made for utilizing the cutter roll shaft as a driving

shaft from which the top rewinding roller can be driven through a variable speed connection and, for this purpose, the other end of the cutter roll shaft is constructed to extend beyond the framework of the machine.

100

105

As is best shown in Fig. 1 of the drawing, the rewinding mechanism comprises the surface rewinding rolls 1 and 2 which are constructed with diameters of such a size that they will form an adequate and rigid support for the rewound coils 3, and the rewinding roll 2 will withstand the strain produced by the pull on the web 4 as it passes around the rewinding roll 2 and 10 is fed directly to the periphery of the rewound coils 3. The rewind shaft 5 forms a core for the rewound coils and is so mounted in the machine that it is free to rise as the diameters of the coils increase. The coil 15 supporting rolls 1 and 2 are rotated in the same direction and coöperate with a driven top rewinding roller 6, rotating in the same direction and bearing against the upper surface of the rewound coils 3, to rotate the interposed coils. The roller 6 is preferably 20 journaled in carriages 7 that are adapted to move upwardly along the vertical guide members 8 in accordance with the increase 25 in size of the rewound coils.

The slitting mechanism preferably 30 comprises the cutter roll 10, having its ends mounted in the end pieces 37 of the machine framework. As will be seen the cutter roll is mounted beneath and intermediate the 35 rewinding rolls 1 and 2, where it coöperates with the cutting disks 12 to slit the web of material 4.

In the practice of the invention the cutter roll 10 is provided with a hardened outer shell made up of sections 9 and, in order to 40 make it possible to replace the ring sections as they become worn, as well as to bodily remove the cutter roll for any reason, without dismantling the machine framework, one of the frame pieces 37 is preferably 45 provided with an opening 45 of sufficient size to give access to the cutter roll and permit the passage therethrough of the cutter sections 9 or of the cutter roll 10 itself. A removable bearing member 36 is adapted 50 to be bolted to one of the frame pieces 37 and to project into the opening 45 to directly support the end of the cutter roll shaft. Temporary supporting means for 55 the cutter roll, such as lifting jacks, can be made use of for sustaining the weight of the roll while the bearing member 36 or the ring sections 9 are being removed.

Advantage is taken of the fact that the 60 cutter roll 10 is mounted directly beneath the top rewinding roller 6, to provide driving connections through which the roller 6 can be driven directly from the cutter roll shaft. For this purpose the cutter roll 65 shaft extends beyond the framework of the machine as is indicated at 58 in Fig. 2 of the drawing.

The driving connection between the top rewinding roller 6 and the extended portion 65 of the cutter roll shaft includes a bevel gear

51 mounted on the shaft of the rewinding roller 6, which meshes with a corresponding bevel gear 52 journaled in a bracket 53 attached to one of the carriages 7. A splined vertical drive shaft 54, journaled at the lower end in a bracket 55 extending outwardly from the machine framework, is so related to the bevel gear 52 that the gear is free to slide vertically along, but is caused to turn with the drive shaft 54 and is adapted to be driven by the shaft 54 in any position which the rewinding roller 6 may take because of the increasing diameters of the rewound coils. The drive shaft 54 is rotated through a bevel pinion 56 meshing with a bevel gear 57, mounted to rotate on the shaft 58 of the cutter roll 10.

In order to vary the speed of rotation of the top rewinding roller 6 to most effectively wind different materials, the bevel gear 57 is driven through a friction clutch from the extension 58 of the cutter roll shaft. This clutch includes the gear 57, the frictionally driven rings 59, the positively driven rings 60, and the positively 90 driven member 61, which is splined at 62 to the cutter roll shaft extension 58. Member 61 carries pins 75 that extend into openings in the rings 60. A hand-wheel 63, attached to a sleeve 64 which is mounted to rotate in the end of the bracket 55, is made use of for varying the effectiveness of the grip of the clutch to thereby control the speed of rotation of the gear 57 and consequently of the top rewinding roller 6.

The sleeve 64 is threaded at one end to give motion to a correspondingly threaded collar 65 secured against rotation by a pin 66 projecting into, and free to slide in, an opening 67 in the lower end of the bracket 55. A spring 68 interposed between the collar 65 and an abutment member 69, free to slide on the shaft 58, conveys motion from the collar 65 to the clutch member 61, as will be obvious. A thumb-screw 70 is 110 used to fix the pin 66 and, hence, the collar 65 in any desired position, a passage-way 71 in the shaft end 58 provides a convenient means for applying lubricant to the rotating parts mounted thereon.

For insuring the complete severance of the web and the separation of the strips, separating members, one of which is shown at 13 in Fig. 1 of the drawing, are employed. This separating member consists of a blade 120 pivotally mounted in a bracket 25 slidably mounted on the supporting bar 26 and adapted to be locked in any desired location by means of the thumb screw 27. The pivotal mounting of the separating blades facilitates the threading of the web, since this arrangement permits the blades to be swung to a position in which they will not intercept the web stretch while the threading operation is being carried out. Preferably the 125

blades are pivoted at a point nearer the web-engaging than the other end, so that gravity tends to bring them to operative position. The structure of the separating device, just described, forms the subject matter of claims in a companion application filed herewith.

In Fig. 1 of the drawing is shown a stripper member 46 which is caused to bear against the surface of the cutter roll. Two such stripper members are employed and they are mounted so as to be adjusted along the supporting shaft 47 to take positions where they will deflect from the roll the narrow trimming strips that are produced at the edges of the web and prevent the carrying of the strips through the rewinding mechanism with the slitted web.

Any suitable driving mechanism may be employed for conveying power to the cutter and rewinding rolls. The driving mechanism illustrated includes the drive pulley 38, the clutch 39 and the fly wheel 40. A pinion 48, integral with the fly wheel 40, meshes with the gear 41 carrying the pinion 49 which meshes directly with gears 42 and 43 on the shafts of the rewinding rolls 1 and 2. The pinion 49 meshes also with the pinion 50 on the end of the cutter roll shaft and the cutter roll shaft in turn drives the top rewinding roller 6 through the friction drive connection already described. In order to facilitate the removal of the bearing member 38 or the ring sections 9, the drive pulley 38, together with the clutch 39 and brake

member 40, as well as the driving gears 41, 42 and 43, are removably mounted on their respective shafts in any suitable manner. By also providing for the removal of the clutch members from the extension 53 of the cutter roll shaft, it will be seen that the cutter roll can be bodily removed from the machine by way of the opening 45 in the opposite side of the frame-work. This result can also be secured by making the clutch-supporting portion of the cutter roll shaft separate from the shaft proper and providing some form of coupling means for coupling or uncoupling the two shafts.

What is claimed, is:

A slitting and rewinding machine comprising: a pair of surface rewinding rolls on which the rewound coils are supported, a cutter roll mounted beneath and intermediate the rewinding rolls, means cooperating with the cutter roll to slit a web into sections, means for causing the web to engage one of the rewinding rolls before it passes to the cutter roll, and web section separating members arranged to engage the slitted web as it passes from the cutter roll to the other rewinding roll.

Signed at Brooklyn, New York city, in the county of Kings and State of New York, this 3 day of May, A. D. 1917.

JAMES A. CAMERON,
GUSTAF BIRGER BIRCH.
